HELICAL GEAR PUMP WITH NONRIGID CASING

Frederick Cameron Byram, New Carlisle, and George H. Zimmer, Jr., Springfield, Ohio, assignors to Robbins & Myers, Inc., Springfield, Ohio, a corporation of Ohio

Application April 29, 1950, Serial No. 159,079

13 Claims. (Cl. 103—117)

1

This invention relates to a helical gear pump having a non-rigid casing. The particular pump to which the invention is applied is a pump of the type disclosed by R. J. L. Moineau in his Patent No. 1,892,217 of December 27, 1932. This pump is of the type having a stator member with internal helical grooves or threads and a rotor member with external helical grooves or threads, the stator member having one thread more than the rotor member. It is one of the characteristics of a pump of this type that if the rotor is rotated on its true center the stator member orbits or wobbles about the rotor member in a cylindrical path.

It is an object of the present invention to provide a pump of the type outlined above for direct connection to an electric motor which pump will be very much cheaper than any pump of this type known heretofore. It is another object of the present invention to provide integrally with the stator member of the pump a member which serves as a portion of the pump casing and intake or discharge whereby an actual pump casing in the conventional sense is eliminated, thereby exhibiting a substantial decrease in manufacturing costs.

Other objects of the invention include the provision of a pump as outlined which in addition to its lower cost will be lighter and smaller than other pumps of this nature heretofore known.

These and other objects of our invention which will be apparent to those skilled in the art upon reading these specifications or which we shall describe in greater detail hereinafter we accomplish by that certain construction and arrangement of parts of which we shall now describe certain exemplary embodiments.

Reference is made to the drawings forming a part hereof and in which:

Figure 1 is a plan view of one embodiment of a pump and motor according to the invention.

Figure 2 is a cross sectional view taken on the line 2—2 of Figure 1.

Figure 3 is an exploded view of a portion of the motor casing and a portion of the pump showing the manner of attachment.

Figures 4 and 5 are fragmentary cross sectional views showing modifications in the manner of attachment.

Figure 6 is a cross-sectional view of another embodiment.

Briefly, in the practice of our invention we mold the pump stator together with an inlet or outlet extension, if required, and the major portion of the pump casing in one piece from a resilient material such as rubber or the like. The

open end of the pump casing portion which surrounds the stator portion is closed by a shallow pan-like head which is provided with a shaft entrance opening and sealing means for the shaft and which is also provided with an aperture for an inlet or outlet port for the pump. The two pump casing portions are secured together by an annular joint and the pump as a whole is secured to an annular extension of the motor casing so that the pump is secured at only the one annular locus. Because of the resilience of the casing portion of the stator the stator portion itself is free to follow the path of movement enforced upon it and a casing in the usual sense of the word is rendered unnecessary. Such a casing may, however, be provided as shown in Figure 6, if it is desired to conceal the wobbling of the stator.

In the drawings, referring now particularly to Figures 1 to 3 inclusive, the motor is generally referred to at 10, and the pump is generally referred to at 11. The motor 10 is preferably provided with an annular frame extension indicated at 12 to which the pump is annularly secured.

The stator element of the pump is indicated at 13 and, as will be clear from an examination of Figure 2, it is provided with a port extension at 14 which is substantially coaxial with the stator portion 13, and it is also provided with a conical casing portion 15 which surrounds the stator portion 13 and extends slightly beyond the end of the stator portion 13. The conical casing portion 15 is provided with an annular flange 16, and preferably the flange 16 is provided with an annular bead 17.

The open end of the conical portion 15 is closed by a shallow pan-like head 18 which may be of light gauge sheet metal or the like and which has an aperture to permit entry of the motor shaft 10a. A collar member 19 is preferably welded to the head portion 18 about the shaft aperture and the shaft preferably is provided with a groove 20 in which a snap ring 21 may engage. Between the collar 19 and the snap ring 21 there is provided a sealing arrangement which may be of more or less conventional design, embodying a gasket 22 and a resilient member 23 held in extended condition by a spring 24. The flange of the resilient member 23 bears against the snap ring 21 and the spring urges the gasket 22 against the collar 19 thus effectively sealing the shaft entrance opening in the head 18.

A port fitting 25 may be brazed, welded or otherwise suitably secured into a port opening 26 in the head 18. It will be clear that the flow of fluid through the pump may be either from right

to left or left to right in Figure 2 depending upon the direction of rotation of the motor shaft 10a.

The rotor member 27 is preferably secured to the motor shaft 10a by a threaded stud 28 on the end of the motor shaft engaging in a threaded bore in the rotor 27.

Assembly may be accomplished in a number of ways, as shown in Figures 3, 4 and 5. The head member 18 may be first secured in place and then the rotor 27 may be assembled to the motor shaft 10a. Thereupon the conical portion 15 may be secured to the head 18, as shown in Figure 3, by an annular grooved ring 29 (the grooves embracing the bead 17 and the head member 18 having a groove member 18a also to accommodate the bead 17) and the ring having an annular extension with suitable holes for the passage of securing bolts 30.

In Figure 4 there is shown a modification wherein the flange of the head member 18 is extended annularly as shown in broken lines at 18b and the flange is first secured in place by means of screws or the like at 31. Thereafter the extension portion 18b is spun over to the position shown in full lines at 18c, thus clamping the flange 16 and bead 17 to the head member 18.

In Figure 5 there is shown a still further modification where an annular clip member 32 is also secured by means of the screws 33 and thereafter the extension 18d of the head flange is spun over to the position shown at 18e.

In operation, when the motor rotates, thus rotating the pump rotor 27, the pump stator 13 is caused to move in a cylindrical path about the axis of the shaft 10a. The resilience of the conical portion 15 of the stator member permits this movement and thus the pump is secured to the motor only in the region of the annular joint between the conical portion 15 and the head member 18. The port extension 14 may be secured in any desired manner to a hose line or the like and, as pointed out above, may serve either as an entrance or exhaust port. The same is true of the fitting 25. In operation thus the entire portions 15 and 14, as observed from the outside, will appear to vibrate at relative high speeds. The pump however is completely sealed from the exterior and has been found to function very efficiently. Since the casing in the conventional sense of the word has been eliminated, the pump is very much lighter and cheaper than any heretofore available.

Since the port fitting 14 will wobble in a cylindrical path along with the stator 13 the hose connections to the fitting 14 will be continually moved. Thus it may be desirable for some purposes that the port fitting remain fixed, and to this end we have shown a modification in Figure 6 wherein the port fitting 14 has been removed from the end of the stator member and the stator member together with its funnel-like casing portion 15, as shown in Figure 2, has been enclosed within a dome-like casing to which a fixed port fitting is secured.

Referring therefore to Figure 6 we have shown the stator 13 with its funnel-like casing portion 15 as before, and the funnel-like portion 15 is provided with the annular flange 16 having the bead 17 as described above. Again the open end of the funnel-like casing portion 15 is closed by a relatively shallow pan-like member indicated at 40 having an annular flange 41 terminating peripherally in a groove 42 for engagement with the bead 17. The member 40 is provided with a port fitting at 43 which may be brazed in place as shown at 44. The member 40 is provided with

a central flanged aperture for the passage of the drive shaft from the motor and the annular flange 45 serves as a support and fastening element for the seal indicated generally at 46.

5 Since the seal forms no part of the present invention it will not be described in detail. The head 40 is suitably secured to a bracket 47 which carries the bearings 48 for the drive shaft 49. The drive shaft 49, as before, may have the threaded end 50 for engagement in the threaded hole 51 of the rotor 27. Thus far in all essential respects the device of Figure 6 is the same as that of Figure 2. It will be observed however that the port fitting 14 has been omitted from the end of the stator 13 and that a member 52 has been provided in the nature of a casing. The member 52 is provided with a peripheral flange 53 which terminates in the annular peripheral groove 54 matching the groove 42 of the head. 10 In assembly the two grooves 54 and 42 embrace the annular bead 17 and these elements are held in assembled relation by means of the clamping ring 55 as shown. The clamping ring 55 may be provided with upstanding ears 56 clamped together by means of nut and bolts indicated generally at 57.

15 The casing member 52 may be spun or drawn from relatively light gauge sheet metal and may have secured thereto, as by brazing or otherwise, the port fitting 58.

20 It will be clear that the only significant change from the device of Figure 2 is in the provision of a supplementary casing 52 with a fixed port fitting.

25 It will be clear that numerous modifications may be made without departing from the spirit of our invention, and we therefore do not intend to limit ourselves in any way whatsoever except as set forth in the claims which follow.

30 Having now fully described our invention, what we claim as new and desire to secure by Letters Patent is:

35 1. A stator for a helical gear pump, comprising an internally helically grooved cylindrical member, and a conical casing member, said casing member, at its small end, merging with one end of said cylindrical member, and towards its large end flaring away from said cylindrical member over substantially the length of said cylindrical member, said stator being of resilient material.

40 2. A stator according to claim 1, having a tubular extension substantially coaxial with said cylindrical member, and extending oppositely to said conical casing member, said extension constituting a port fitting.

45 3. A stator for a helical gear pump, comprising an internally helically grooved cylindrical member, and a conical casing member, said casing member, at its small end, merging with one end of said cylindrical member, and towards its large end flaring away from said cylindrical member over substantially the length of said cylindrical member, and having at its flaring end an annular beaded flange, said stator being of resilient material.

50 4. A stator according to claim 3, having a tubular extension substantially coaxial with said cylindrical member, and extending oppositely to said conical casing member, said extension constituting a port fitting.

55 5. A helical gear pump comprising a stator member constituted of an internally helically grooved cylindrical member, and a conical casing member, said casing member, at its small end, merging with one end of said cylindrical mem-

ber, and towards its large end flaring away from said cylindrical member over substantially the length of said cylindrical member, said stator being of resilient material, a pan-like casing element for closing the flaring end of said casing member, said pan-like casing element having a shaft entrance opening and having also a port opening for said pump, a shaft entering said shaft entrance opening, and an externally helically grooved rotor element secured to said shaft within said casing members, said one end of said cylindrical member constituting also a port opening for said pump.

6. A pump according to claim 5, wherein a tubular extension constituting a port fitting is provided on said cylindrical member substantially coaxial therewith, and extending oppositely to said conical casing member, and wherein said pan-like element and conical element together constitute the entire pump casing.

7. A pump according to claim 5, wherein there is provided a covering member secured to said pan-like element and covering and concealing said stator member, said covering member having a port fitting.

8. The pump of claim 5 in combination with an electric motor, said shaft being the shaft of said motor, and said motor having an annular frame extension, and said casing elements being annularly secured to said frame extension.

9. A helical gear pump comprising a stator member constituted of an internally helically grooved cylindrical member, and a conical casing member, said casing member, at its small end, merging with one end of said cylindrical member, and towards its large end flaring away from said cylindrical member over substantially the length of said cylindrical member, said stator being of resilient material, a pan-like casing element for closing the flaring end of said casing member, said pan-like casing element having a shaft entrance opening and having also a port opening for said pump, a shaft entering said shaft entrance opening, and an externally helically grooved rotor element secured to said shaft within said casing members, said one end of said cylindrical member constituting also a port opening for said pump, said conical casing member and pan-like casing element being joined and sealed annularly, and said pump being fixed to a

5 support annularly in the region of said annular joint.

10. A pump according to claim 9, wherein a tubular extension constituting a port fitting is provided on said cylindrical member and substantially coaxial therewith, and wherein said pan-like element and conical element together constitute the entire pump casing.

11. A pump according to claim 9, wherein there is provided a covering member secured to said pan-like element and covering and concealing said stator member, said covering member having a port fitting.

12. The pump of claim 9 in combination with an electric motor, said shaft being the shaft of said motor, and said motor having an annular frame extension, and said pump being secured to said annular frame extension in the region of said annular joint.

13. A helical gear pump comprising an externally helically grooved rotor element, means for rotating said rotor element on its true axis, a stator member comprising an internally helically grooved cylindrical element, and means mounting said stator member to permit the movement thereof in its enforced cylindrical path, said means comprising a casing portion of resilient material, secured adjacent an end thereof to said stator member, said casing portion being secured also to a second casing portion of rigid material, said rigid casing portion having a bearing for said rotor axis, and having a port opening.
